CLAIM

The ornamental design for an ultraviolet treatment apparatus, substantially as shown and described.

DESCRIPTION

FIG. 1 is a front view of an ultraviolet treatment apparatus;
FIG. 2 is a rear view of the ultraviolet treatment apparatus;
FIG. 3 is a left side view of the ultraviolet treatment apparatus;

FIG. 4 is a bottom view of the ultraviolet treatment apparatus;

FIG. 5 is a top view of the ultraviolet treatment apparatus;
and,

FIG. 6 is a perspective view of the ultraviolet treatment apparatus.

1 Claim, 6 Drawing Sheets

FIG. 1

FIG. 2

FIG. 3

FIG. 4

FIG. 5

FIG. 6
